CLAIM

The ornamental design for a toy power drill, as shown and described.

DESCRIPTION

FIG. 1 is a rear perspective view of a toy power drill showing my new design;

FIG. 2 is a right side elevational view of the toy power drill of FIG. 1;

FIG. 3 is a left side elevational view of the toy power drill of FIG. 1;

FIG. 4 is a top plan view of the toy power drill of FIG. 1; FIG. 5 is a bottom plan view of the toy power drill of FIG. 1;

FIG. 6 is a front elevational view of the toy power drill of FIG. 1;

FIG. 7 is a rear elevational view of the toy power drill of FIG. 1;

FIG. 8 is a front perspective view of the toy power drill of FIG. 1; and,

FIG. 9 is a front perspective view of the toy power drill of FIG. 1 without the exemplary hex socket bit.

The broken lines in the drawings illustrate portions of the toy power drill and an environmental hex socket bit that do not form part of the claimed design.
